UNITED STATES PATENT OFFICE.

AMOS W. BROWN, OF LANSINGBURG, NEW YORK.

BLACKING-BRUSH.

SPECIFICATION forming part of Letters Patent No. 375,336, dated December 27, 1887.

Application filed March 21, 1887. Serial No. 231,745. (No model.)

To all whom it may concern:

Be it known that I, AMOS W. BROWN, a citizen of the United States, residing at Lansingburg, in the county of Rensselaer and State of New York, have invented a new and useful Improvement in Blacking-Brushes, of which the following is a specification.

My invention relates to improvements in blacking-brushes; and it consists in a certain novel construction, fully set forth hereinafter and claimed.

In the accompanying drawings, Figure 1 is a perspective view of my improved brush. Fig. 2 is a top plan view of the same, showing the manner of operating in dotted lines. Fig. 3 is a central longitudinal section.

Referring to the drawings, in which similar letters denote corresponding parts in all the figures, my improved brush consists of three independently-arranged parts or sections—namely, the lower section, A, comprising a handleless polishing-brush of the ordinary construction and shape; the central section, B, comprising an independently-adjustable back for the lower section, and conforming to the general contour of the said lower section, said central section being extended to form the handle D; and the upper section, C, provided with the daubers E E' at the opposite ends thereof.

Through the central points of the three sections is passed a bolt, F, provided on the upper end with the nut F', adapted to clamp the said sections in the desired position. This bolt is securely seated in the lower section, A, and held from independent rotary movement.

It will be seen that the sections A B C are entirely independent of each other, any one of which may be revolved while the other two remain stationary.

Thus the advantages of my invention will

be evident—namely, the independently revolvable and adjustable back may be applied to any handleless polishing-brush; the independent upper section having the daubers 45 may be revolved when one dauber is worn out, to bring the other into position for use, and the lower section or polishing-brush may be also revolved at intervals to cause the wear on the brush to be more uniform. The appearance 50 of the brush when the sections are secured in position for use is very neat, as all the parts conform to the general shape of a brush. Thus I have produced an article which, although possessing all the advantages herein claimed 55 for it, is made so compactly that the appearance is exceedingly light and neat.

My brush can be manufactured very cheaply, and, in addition to this, it will be found to be an extremely economical brush, in that the 60 adjustable handle and back combined, being detachable, may be used on successive brushes, and by providing two daubers the brush will last twice as long as the ordinary brush, as that is the part which wears out first, the polishing-brush ordinarily outlasting it.

Having thus described my invention, what I claim, and desire to secure by Letters Patent of the United States, is—

A brush comprising the back B, having a 70 handle, D, at one end, the polishing-brush pivoted on one side of the back, and the section C, pivoted on the opposite side of the back and having the daubers at its ends, substantially as described.

In testimony that I claim the foregoing as my own I have hereto affixed my signature in presence of two witnesses.

AMOS W. BROWN.
